UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,324,085.

Specification of Letters Patent.

Patented Dec. 9, 1919.

Application filed April 12, 1918. Serial No. 289,626.

To all whom it may concern:

Be it known that I, FRANKLIN R. WHITE, a citizen of the United States, and a resident of Waterbury, in the county of New Haven and State of Connecticut, have made and invented certain new and useful Improvements in Buttons, of which the following is a specification.

My invention relates to a new and useful improvement in buttons and particularly to that type or kind thereof which is employed with a tack which is adapted to pierce its way through an imperforate base and be guided in its upward passage by an anchor located in said button and impinge or flatten against an anvil also located in said button and above said anchor and in which a top plate is placed over the body of the button to tightly hold the anchor and anvil in place and complete the button.

The purpose of placing an anvil in the button is so that the top plate will not be perforated or marred by the passage of the tack into the button, and the purpose of the anchor is to provide another point of contact with the tack and to more rigidly hold the button against the cloth than would be possible if the tack simply perforated the base plate. This invention is also similar to a button for which an application for U. S. Letters Patent has been executed by me of even date herewith.

An object of the present invention is to provide a button which may be cheaply manufactured, easily assembled, and which will be held tightly in place after the button is secured to the cloth.

Another object of my invention is to provide a novel form of anchor so that the tack will be held in its upright position after piercing the base plate even should it tend to deflect after it perforates the base plate.

Still another object of my invention is to so construct the anchor that it will bear against the anvil and thereby prevent the same from rattling or shaking in the button, and to so construct the anchor that when the button is assembled the same will be forced snugly and tightly into the shell of the button.

Referring to the drawings, Figure 1 is a sectional view, and partly in elevation, of the button, cloth and tack before the same are assembled;

Fig. 2 is a similar view, the button and

tack, however, in this instance being in their final or assembled positions;

Fig. 3 is a top plan view with a portion of the top plate and anvil being broken away for the sake of clearness;

Fig. 4 is a bottom plan of the anchor;

Fig. 5 is a perspective of the anvil; and

Fig. 6 is a bottom plan of a slightly modified form of the anchor.

Referring now to the drawings, it will be seen that the button consists of the body portion 1 with a downwardly extending hub 2 in the form of a hollow shell, the upper part of the body portion being flared outwardly as at 3. Resting within the body portion is a circular anvil plate 4 to deflect the point of a tack 5 after piercing the base plate of the button.

Before this tack 5, however, is deflected, it must pierce an anchor 6 which is formed with a central impression 7 which is similar to an impression 8 formed in the bottom 9 of the hub 2. This anchor is preferably stamped from a thin ribbon of steel and is similar in contour to the hub of the button, but when stamped from the ribbon it is stamped with the upper outline being practically in the form of a square in plan with the centers slightly cut out as at 11, which provides the spring arms 12. These arms 12 extend slightly upwardly, so that when this anchor is first placed in the hub of the button the arms 12 will not lie flat in the button but extend slightly upwardly and contact with the anvil 4. These arms, being of steel, will have a certain amount of spring and resiliency. A top plate 10 is provided which is forced on and tightly clamps the flared portion 3 of the button; also the anvil will compress the resilient spring arms 12 and this constant compression of the spring arms against the anvil will hold the anvil against the top plate, thereby preventing any rattling of the anvil in the button.

By providing the central impression 8 in the base of the hub 9 the point of the tack 5 will pierce the central portion of the base, and if for any reason it should not be in correct alinement when starting it will be necessarily guided upwardly by the side walls of the impression and pierce the central portion thereof, as clearly shown in Fig. 2.

If for any reason the point of the tack 110

should become deflected after piercing the bottom of the button, which often happens in buttons of a somewhat similar type, the point again will be correctly alined by the side walls of the impression 7 in the anchor 6, so that the tack after piercing the central impression 8 of the bottom 9 and the central impression 7 of the anchor 6, will be in a correct vertical position. The point 10 will then impinge against the anvil 4 and be jammed or forced downwardly over the upper surface of the anchor 6, also tightly holding the anchor and complete button in position, the end of the tack extending over 15 into the anchor.

In Fig. 6 there is shown a modification of the anchor, in this instance it being similar to the anchor shown in Fig. 4, with the exception that it is not provided with the 20 outwardly extending arms 12 but simply comprises the hollow shell 13, with the side walls 14 and the central impression 15.

From the foregoing it will be seen that I have provided a button which is relatively 25 cheap to manufacture; which has a plurality of points of contact with the tack, which contacts are in a spaced relation from each other, thereby rigidly securing the button to the cloth; and I have also provided a button 30 wherein the tack will be correctly alined throughout its entire movement both through the base plate and through the anchor until it finally impinges against the anvil and is deflected over the upper surface 35 of the anchor, and also by forming the anchor as shown, with the resilient spring arms, the same is always in its correct place, cannot be drawn down by the rivet when the button is being fastened to the cloth; and, 40 furthermore, the anvil will be held up by the spring arms 12 against the top plate, thereby preventing any rattling of the anvil in the button.

Having thus described and explained my 45 invention, I claim as new and desire to secure by Letters Patent:

1. A button comprising a body portion having a hub in the form of a hollow shell,

and an imperforate base plate with a centrally formed impression; an annular anchor fitting within said hub portion, and the base plate of which is a replica of the base plate of the hub portion; an anvil located above said anchor, and a top plate wedgedly connected to said body portion. 50

2. A button comprising a body portion having a hub in the form of a hollow shell and an imperforate base plate, an indentation formed centrally of the imperforate base plate, and an anchor likewise provided 60 with an indentation in the bottom thereof and in direct alinement with the indentation formed in the base plate of the hollow hub; an anvil located in the body portion of said button, and a top plate secured to said body 65 portion after said anvil and said anchor are in position.

3. A button comprising a body portion having a hub with an imperforate base plate, an indentation formed centrally of said imperforate base plate, an anchor comprising 70 a hub and an imperforate base plate with an indentation in said base plate in alinement with the indentation on the base plate of the body portion, and an anvil located in the 75 body portion of said button and fixedly connected thereto.

4. A button comprising a body portion having a hub in the form of a hollow shell and an imperforate base plate with a centrally formed impression; an anchor fitting within said hub portion having an imperforate base plate with a centrally formed impression therein, said anchor including a plurality of outwardly extending spaced arms 80 engaging the body portion of said hub at spaced points, and an anvil located above said top plate and fixedly secured to the body portion of said button. 85

Signed at Waterbury, in the county of 90
New Haven and State of Connecticut, this
2nd day of April, A. D. 1919.

FRANKLIN R. WHITE.
